GEORGE W. HULSHIZER, OF STEWARTSVILLE, NEW JERSEY, ASSIGNOR TO INGERSOLL-RAND COMPANY, OF JERSEY CITY, NEW JERSEY, A CORPORATION OF NEW JERSEY

CLAMP

Application filed August 22, 1929. Serial No. 337,666.

This invention relates to clamps, but more particularly to a clamp adapted to be supported by a column or similar device and to itself form a support for a rock drill.

One object of the invention is to enable the clamp to be quickly clamped to a supporting column or to be released therefrom.

Another object is to assure an adequate pressure which may be readily applied for clamping the jaw elements of the clamp together.

Other objects will be in part obvious and in part pointed out hereinafter.

In the drawings illustrating the invention and in which similar reference characters refer to similar parts,

Figure 1 is a side elevation of a drilling apparatus equipped with a clamp constructed in accordance with the practice of the invention, and

Figure 2 is a sectional transverse view through the clamp.

Referring to the drawings, A represents generally the clamp which is supported in this instance by an arm B of a drill column C interposed between the floor D and the roof E of a mine or drift F.

The clamp A supports a shell G wherein is mounted a rock drill H carrying a working implement, such as a drill steel J, for drilling holes K in the material L.

In accordance with the present invention, the clamp A comprises a casing O, in one end of which is a cylinder P and at the other end an integral clamp portion Q preferably having an inner curved surface R of substantially the same conformation as the periphery of the arm B whereon the clamp is mounted.

The curved surface R forms one side of a recess S in the casing O, and said recess has opposed surfaces T and U which are tangent to the curved surface R and serve as bearing surfaces for the ends of a jaw V disposed slidably in the recess S.

The jaw V is also provided with a curved surface W to bear against the periphery of the arm B. In one side of the jaw V is a slot X into which projects the end of the key Y threaded into the casing O to maintain the jaw in the casing O during such time as

the clamp may be detached from the column arm.

Disposed in the cylinder P is a piston Z having a rod b attached thereto and said rod b extends through a bore c in the casing and is adapted to abut the jaw V for moving said jaw relatively to the jaw portion Q. Any suitable closure may be provided for the open end of the cylinder P, as for instance a plug d threaded into the end of the cylinder.

Suitable means are provided for compressing fluid, such as oil or water, and for pumping such fluid into the cylinder P for actuating the piston Z and thus also the jaw V. To this end a chamber e is formed in the casing O and said chamber communicates with the cylinder P through a passage f. The casing O is further provided with a supply reservoir g for oil or water h and said supply reservoir communicates with the chamber e through a passage j.

The means whereby the fluid h may be drawn from the reservoir into the chamber e and compressed therein and pumped into the cylinder P may consist of a plunger k having a stem o which extends slidably through a sealing plug p in the outer end of the chamber e.

To the free or projecting end of the stem o is pivoted a link q which is pivoted at its other end to a lever r whereby the plunger k may be manually actuated. The lever r may be in the form of a bell crank and one end thereof may be pivoted to the casing O as at s. In order to at all times maintain the lever r in the correct position for pumping fluid from the chamber e into the cylinder P a spring t may be seated in the bottom of the chamber e to act against the end of the plunger k.

Any suitable means, as for instance spring pressed ball valves u and v, may be disposed in the passages j and f respectively for preventing the return of fluid from the chamber e into the reservoir g and also from the cylinder P into the chamber e.

To the end that an adequate supply of fluid may be drawn from the reservoir into the chamber e by the plunger k in any of the various positions which a clamp of this char-

acter may assume in practice, a tube w is threaded into the casing to project into the reservoir g , and said tube is provided with a plurality of ports x through which the fluid 5 may enter the tube. The fluid which the reservoir g is intended to accommodate may be introduced through an opening y normally sealed by a plug z .

As will be observed the passages between the 10 supply reservoir g and the cylinder P constitute a one-way channel between these elements. In order therefore to again permit the return of the fluid into the supply reservoir the casing O is provided with an exhaust 15 passage 2 which leads directly from the cylinder P to the reservoir g and is controlled by a throttle valve 3 disposed rotatably in the casing.

In order to clamp the casing O to the shell 20 G which it is adapted to support said casing is provided with an integral clamping member 4 having a conical surface 5 to conform to the surface of a cone 6 carried by the shell G and a removable clamping member 7 having 25 a conical surface 8 to bear on the cone 6 is adapted to bear with its other end against the jaw portion Q . The clamping member 7 may be clamped in position in any suitable manner, as for instance, by a bolt 9 threaded 30 into the casing and having a nut 10 threaded thereon to bear against the member 7 .

In practice, whenever it is desired to fasten the clamp A on a column or arm, such as the arm B , the lever r may be manipulated for 35 drawing liquid from the supply reservoir into the chamber e and also for compressing such liquid and pumping it through the passage f into the cylinder P to act against the piston Z . Upon completion of a drill hole, after 40 which it may be desirable to change the position of the drilling mechanism on the arm B , the throttle valve 3 may be manipulated to release a portion or all of the fluid under pressure in the cylinder P and such fluid will then 45 return in the reservoir through the passage 2 .

I claim:

1. In a clamp, a casing having a jaw portion, a jaw slideable in the casing to cooperate with the jaw portion for securing said clamp 50 to a support, pressure actuated means for actuating the jaw and the jaw portion with respect to each other, a chamber in the casing connected with the pressure actuated means, a plunger in the chamber for compressing 55 fluid and for pumping such fluid to the pressure actuated means, and means for actuating the plunger.

2. In a clamp, a casing having a jaw portion, a jaw in the casing, pressure responsive 60 means in the casing associated with the jaw, a supply reservoir for fluid in the casing, a chamber in the casing, passages leading from the chamber to the supply reservoir and the pressure responsive means, means in the 65 chamber for compressing fluid and for pump-

ing such fluid into the pressure responsive means to actuate the jaw with respect to the jaw portion, and means responsive to the pressure of fluid admitted into the pressure responsive means for preventing unintentional return flow of such fluid from the pressure responsive means into the reservoir.

3. In a clamp, a casing having a jaw portion, a jaw in the casing, pressure responsive means in the casing associated with the jaw, 75 a supply reservoir for fluid in the casing, a chamber in the casing, passages leading from the chamber to the supply reservoir and the pressure responsive means, means in the chamber for compressing fluid and for pumping such fluid into the pressure responsive means to actuate the jaw with respect to the jaw portion, valves responsive to the pressure of fluid admitted to the pressure responsive means for preventing 80 the return flow of fluid from the pressure responsive means through the passages into the reservoir, an exhaust passage in the casing leading from the pressure responsive means, and a valve to control the exhaust passage. 85

In testimony whereof I have signed this specification.

GEORGE W. HULSHIZER.
